US0D1040450S

(12) **United States Design Patent** (10) **Patent No.:** **US D1,040,450 S**
(45) **Date of Patent:** **** Aug. 27, 2024**

(54) **ANIMAL TRAINING DEVICE**

(71) Applicant: **Shannon East**, San Jose, CA (US)

(72) Inventor: **Shannon East**, San Jose, CA (US)

(**) Term: **15 Years**

(21) Appl. No.: **29/845,132**

(22) Filed: **Jul. 5, 2022**

(51) **LOC (14) Cl.** **30-99**

(52) **U.S. Cl.**

USPC **D30/199; D10/104.1**

(58) **Field of Classification Search**

(57) **CLAIM**

The ornamental design for an animal training device, as
shown and described.

DESCRIPTION

FIG. 1 is a front, top, and right side perspective view of an
animal training device, showing my new design;
FIG. 2 is a front, top, and left side perspective view thereof;
FIG. 3 is a front, bottom, and right side perspective view
thereof;

FIG. 4 is a front, bottom, and left side perspective view
thereof;

FIG. 5 is an elevational front view thereof;

FIG. 6 is an elevational rear view thereof;

FIG. 7 is an elevational left side view thereof;

FIG. 8 is an elevational right side view thereof;

FIG. 9 is an elevational top view thereof; and,

FIG. 10 is an elevational bottom view thereof.

Broken lines are for illustrative purposes only, and form no
part of the claimed design.

1 Claim, 10 Drawing Sheets
